UNITED STATES PATENT OFFICE.

ISHMAEL G. CUTRIGHT AND JOHN A. SHARPS, OF BUCKHANNON, WEST VIRGINIA.

METAL SHADE SLAT.

Application filed April 28, 1921. Serial No. 465,187.

To all whom it may concern:

Be it known that ISHMAEL G. CUTRIGHT and JOHN A. SHARPS, citizens of the United States, residing at Buckhannon, in the county of Upshur and State of West Virginia, have invented certain new and useful Improvements in Metal Shade Slats, of which the following is a specification.

This invention relates to new and useful improvements in shade or curtain slats, the primary object of the invention being to provide a slat constructed of sheet metal.

An important object of the invention is to provide a metallic slat formed by folding a strip of sheet metal and to so arrange the free longitudinal edges of the strip that they will not present sharp edges to damage the fabric with which the slat is associated.

Another object of the invention is to provide a metallic slat which is light, strong and durable, inexpensive to manufacture and which will maintain the shade with which it is associated in a perfectly flat condition when unwound from its roller.

Other objects and advantages of the invention will become apparent during the course of the following description.

In the accompanying drawing forming a part of the application and wherein like numerals are employed to designate like parts throughout the several views.

Figure 1 is a side elevation of one end of the improved slat, a portion of a curtain shade and the hem thereof being shown in dotted lines.

Figure 2 is a transverse section of the same.

In the drawings wherein for the purpose of illustration is shown the preferred embodiment of the invention, the numeral 3 designates a portion of the ordinary cloth window shade having its lower edge provided with the usual hem 4 which provides the shade with a transversely extending pocket for the reception of a slat.

As well understood, a slat forms an indispensable part of the ordinary window curtain shade in order to prevent the shade from being crumpled, cracked and creased, and also provides a weight for the free lower edge of the shade to prevent the same from curling up as induced by the rolling of the shade upon its roller.

The slats now in use in curtain shades are constructed of exceptionally light wood and which possess very many bad features

which can be effectively overcome by metallic slats constructed in the proper manner. The old wooden slats are in the first place liable to break, and when they are broken 60 the fractured ends present very rugged projections which will eventually punch through the cloth fabric if such has not already occurred with the breaking of the slat. Furthermore, these wooden slats very 65 often warp due to both dampness and lack of moisture. Such warping would of course impair the neat appearance which the ordinary window shades are capable of making when the slats are in perfect condition. 70 Other than these points, it will be obvious that a wooden slat could not possibly be used for theater curtains and moving picture screens, whereas a comparatively light and durable metallic slat would effectively 75 serve the purpose.

It is therefore with these points in mind that the present slat has been devised. This slat is constructed from a strip 5 of sheet metal which is folded longitudinally as at 6 80 to present a relatively broad convex edge. By thus folding the strip, a pair of sides 7 and 8 are provided for the slat and these sides are disposed in converging relationship to meet in a longitudinal edge as clearly 85 seen in Figure 2. Of course, it will be understood that the slat may be bent into any other cross sectional shape desired, but in the present instance we have selected the shape illustrated and which conform, to the general outline of the wooden slat now in use. 90

In order that the longitudinal edges of the strip will not present edges which will break through the cloth fabric of the shade, the longitudinal marginal edge of the side 95 8 is bent over the free edge 10 of the side 7 where it meets the side 8. This will of course conceal the free edge 10 of the side 7, and marginal edge 9 of the side 8 is caused to lie in close contact with the longitudinal 100 marginal edge of the side 7. It will be noted that the marginal edge 9 extends a substantial distance upon the side 7 so that the free edge of the margin 9 will not present a cutting surface. By the particular manner in which the longitudinal marginal edges of the strip of sheet metal are associated, it will be seen that they will be securely interlocked and that there is no possibility of the sides of the slat spreading. 105 It will also be appreciated that a hollow slat is provided by the present in-

vention which is comparatively light, one which will not break under any condition or cut through the fabric shade, one which will not warp, and a slat which may be used with 5 equal facilities and advantages in both a small type of curtain and one such as is used in theaters and in conjunction with moving picture screens.

The foregoing description and accompanying drawings have reference to what might be considered to be the approved or preferred form of our invention. We desire it to be understood that we may make such changes in the construction, combination and arrangement of parts, materials, dimensions, etc., as may prove expedient and fall within the scope of the appended claim.

Having thus described our invention what we claim as new and desire to secure by Letters Patent is:

The combination with a window shade having a hem formed in its lower end defining a slat receiving pocket open at both ends, of a slat adapted to fit in the pocket formed of a single strip of metal including an 25 arcuate lower wall for engaging the bottom wall of the pocket, converging side walls for engaging the side walls of the pocket, and a flange formed on the upper longitudinal edge of one side wall for engaging over the 30 upper longitudinal edge of the upper side wall and for engagement with the upper wall of the pocket.

In testimony whereof we affix our signatures in presence of two witnesses.

ISHMAEL G. CUTRIGHT.
JOHN A. SHARPS.
